UNITED STATES PATENT OFFICE.

HARLEY H. DULEY, OF DETROIT, MICHIGAN, ASSIGNOR TO GENERAL FIRE EXTINGUISHER COMPANY, OF NEW YORK, N. Y., A CORPORATION OF NEW YORK.

AUTOMATIC SPRINKLER.

1,412,172.

Specification of Letters Patent. Patented Apr. 11, 1922.

Application filed December 13, 1916. Serial No. 136,777.

To all whom it may concern:

Be it known that I, HARLEY H. DULEY, a citizen of the United States, residing at Detroit, in the county of Wayne and State 5 of Michigan, have invented new and useful Improvements in Automatic Sprinklers, of which the following is a specification.

This invention relates to automatic 10 sprinklers of that class in which the water discharge nozzle is closed by a cap normally held from opening under the confined water pressure by a cap retaining device, including means normally maintaining the retaining device in operative position and adapted 15 under the action of heat to be rendered inoperative, so that the retaining device will release the cap and permit it to open for the discharge of water to extinguish the flames.

20 The object of the invention is to provide a cap retaining device which is simple of construction, positive, reliable and efficient in action, and which, while guarding against the release of the cap until a predetermined 25 degree of heat has been reached, will release the cap with certainty when such temperature is reached for the reliable and certain discharge of the water.

The invention consists of the features of 30 construction, combination and arrangement of parts hereinafter fully described and claimed, reference being had to the accompanying drawing in which:—

Figure 1 is a sectional elevation of an 35 automatic sprinkler embodying my invention, and showing the parts of the retainer in full and dotted lines in normal holding and releasing positions.

Figure 2 is a sectional elevation of the 40 automatic sprinkler taken substantially on the plane indicated by the line 2—2 of Figure 1.

Figure 3 is a perspective view of the parts 45 of the retainer removed and disposed in assembled relation.

Figure 4 is a perspective view of the lever member of the retaining device.

Figures 5 and 6 are, respectively, similar 50 views of the post or strut and the retaining plate forming part of the releasing device.

Figure 7 is a top plan view of the cap.

Referring to the drawing, 1 designates a nozzle provided with a screw threaded portion 2, by which it may be connected with 55 a pipe containing water under pressure.

This nozzle is adapted to be closed by a cap 3 between which and its seat 4 at the discharge end of the nozzle may be interposed a sealing disk, or gasket 5, of copper or other suitable material. The cap 3 is in the 60 form of a circular disk having a central depression 6, for a purpose hereinafter described.

Rising from the nozzle are curved arms 7 connected at their upper ends by an internally threaded collar 8 which receives an adjusting or tensioning screw 9 having a conical lower end 10, said screw being provided at its upper end with a head 11 of suitable form supporting the usual deflector 70 or diffuser 12. A set pin or screw 13, of a suitable type, may be provided for locking the adjusting or tensioning screw in adjusted position against shifting movement.

The cap 3 is designed to be held in closed 75 position against the water pressure by means of a retaining device. This retaining device consists of an upright post or strut 14 of approximately triangular form and having an upper obliquely bent end 15, the lower end 80 of said strut terminating in a reduced portion 15' of less width than the bottom portion of the body of the strut, whereby shoulders 16 are formed at the opposite sides of said portion 15'. The lower edge of the portion 15' is designed to engage the recess 6 in the cap 3, so as to exert bearing pressure 85 thereon so as to hold the cap in position.

Supported by the post or strut 14 is a lever 17 having upper and lower arms 18 and 90 19. The arm 18 is relatively shorter than the arm 19, and said arms are disposed in parallel relation with their free edges in vertical alinement, the opposite ends of the arms being connected by the body portion 95 of the lever which extends at oblique angles thereto. The arm 18 is formed with a depression 20 which receives the conical end 10 of the screw 9 and forms a seat recess 21 at the angle of intersection of said arm with the body portion of the lever 19, which recess 21 receives the upper end of the angular arm 15 of the post or strut 14. The lower arm 19 of the lever is provided with a central recess 22 and lugs 23 projecting on 100 opposite sides thereof, which lugs are formed with receiving sockets or openings 24.

The recess 22 receives the reduced end 15' of the post or strut 14, the shoulder 16 of which rests against the upper surface of the 110

arm 19, whereby when the post and lever are held in fixed relationship the tendency of such parts to tilt under the pressure of the cap will be overcome and the cap held in 5 closed position. For the purpose of maintaining the cap and strut normally in fixed relationship, I provide a retaining plate 26, which is preferably of frusto-triangular form and is arranged to rest upon the lugs 10 23 and against the outer surface of the body of the strut 14 and is provided with retaining lugs or projections 27 to engage the sockets or openings 24 in the arm 19, whereby to positively connect the strut and lever 15 together. The retaining plate is normally secured to the face of the strut 14 by the use of a suitable fusible medium 28, such as solder, which is designed to melt at a predetermined degree of heat, thus holding the 20 parts of the retainer assembled against any tendency to collapse under ordinary conditions, the retainer thus acting as a rigid device held by the screw 9 with a proper degree of pressure against the cap 3 to prevent said cap from opening under the water 25 pressure, as will be readily understood.

In the normal position of the parts shown in full lines in Figure 1, it will be seen that the retainer composed of the parts described 30 held united in the stated manner will bear firmly against the cap and thus hold it closed. When, however, the solder 28 is subjected to a predetermined degree of heat, as through the breaking out of a fire in the 35 immediate vicinity of the sprinkler, the retainer plate 26 will be released from positive connection with the post or strut and will tilt outwardly by its own weight, and the tendency of the lever 17 to tilt upon the angular end 15 of the post or strut 14, thus disturbing the stability of said post or strut 40 which is displaced by the pressure of the

fluid on the cap 3, so that the retainer as a whole will be collapsed or tilted out of holding position, thus allowing the cap 3 to be 45 forced open for the discharge of the water. It will be evident, however, that until the fusible connecting medium is melted the retainer plate will hold the parts of the retainer assembled rigidly as a unit, so that 50 the cap may be held closed against any possibility of opening under any desired pressure imposed by the screw 9, whereby any premature collapse of the retainer and opening of the cap will be avoided. It will be 55 seen that the construction of retainer for securing this end is simple and that the parts are capable of being easily and conveniently assembled, and that the rigidity of connection of the parts under normal conditions is 60 ensured by reason of their interengaging connection. Furthermore, it will be seen that as soon as the retainer plate is released by the melting of the fusible medium, an instantaneous collapse of the retainer will be 65 established, ensuring the positive and reliable opening of the cap.

I claim:—

In an automatic sprinkler, the combination of a nozzle, a cap for closing the nozzle, an adjustable tensioning screw, a lever having a short upper arm engaging said screw and a longer lower arm provided with a central recess and apertured lugs at opposite sides thereof, a strut having a reduced 70 end passing downward through said recess and engaging the cap and an angular upper end engaging the short arm of the lever, a retaining plate having projections engaging the apertures in the lugs of the lever, and a 75 fusible connection between said retaining plate and the strut.

In testimony whereof I affix my signature.
HARLEY H. DULEY.
